UNITED STATES PATENT OFFICE.

JOHN K. STEWART, DECEASED, LATE OF CHICAGO, ILLINOIS, BY JULIA B. STEWART,
EXECUTRIX, OF NORTHPOR, NEW YORK.

DRIVE-CHAIN.

1,269,656.

Specification of Letters Patent. Patented June 18, 1918.

Application filed October 14, 1916. Serial No. 125,646.

To all whom it may concern:

Be it known that I, JULIA B. STEWART, a citizen of the United States, residing at Northport, in the county of Suffolk and State of New York, am the executrix of the last will and testament of JOHN K. STEWART, late resident of Chicago, Illinois, deceased, who had invented new and useful Improvements in Drive-Chains, of which the following is a specification, reference being had to the accompanying drawings, forming a part thereof.

This invention relates to drive chains for power transmission purposes and is especially concerned with the multi-plate style of chain in which each link is composed of a plurality of plates arranged side by side and separated from each other so as to be interspersed with the similarly arranged plates of the next link at the joint between the two links. The invention consists in the features and elements and their combinations shown in the drawings and herein-after described as indicated by the claims.

25 In the drawings:

Figure 1 is a side elevation of a section of chain embodying this invention.

Fig. 2 is a top plan view partly in section.

30 Fig. 3 is a side elevation of one of the plates of which the chain links are formed.

Fig. 4 is a side elevation of the same plate showing the opposite side thereof.

Fig. 5 is a side elevation of a portion of chain having a modified form of rocker bearing.

Fig. 6 is a top plan view partly in section at the joint of the chain shown in Fig. 5.

Fig. 7 is a side elevation of a single link plate used in the chain shown in Fig. 5.

Fig. 8 is a side elevation of another form of link plate.

Figs. 9 and 10 are side elevations of modified forms of link plates.

45 The drive chain which is illustrated in Fig. 1, is composed of links, A, having teeth, A¹, which may be so designed and related as to correctly fit the teeth of standard involute gears of various diameters resulting in comparatively quiet running upon such gears from which this type of chain has come to be known as a "silent chain." This feature, however, is only incidental and is not essential for the purposes of the present invention.

As indicated in Figs. 2, 3 and 4, each of the plates, a, of which the chain links are composed is formed of flat stock with a bearing lug, a¹, struck out of said stock near each end of the link and projecting from one face thereof by a distance substantially equal to the thickness of the material from which the link is formed. These lugs, a¹, are curved and a considerable aperture, a², whose general shape is triangular with curved sides, is formed in the plate extending from the convex side of the lug, a¹, toward the middle portion of the plate. From Fig. 2 it will be seen that the plates, a, are assembled so that for each link of the chain the lugs, a¹, of all the plates, a, composing that link extend laterally in the same direction while the lugs, a¹, of the next link extend laterally in the opposite direction and project into the apertures, a², of the first link plates. Or considering simply one pair of plates, a, belonging respectively to adjacent links of the chain, the joint between said two plates is formed by the convex side of the lug, a¹, of one plate engaging the convex side of the lug, a¹, of the other plate, while the laterally projecting portions of said lugs are accommodated in the clearance apertures, a², of such plates. The lugs, a¹, thus furnish a rocking bearing between the plates thus connected which is simply duplicated in every other similar pair of plates in the chain.

Thus a single joint of the chain such as is shown in section in Fig. 2 comprises a number of pairs of plates, a, each pair being connected together by a rocking joint formed of their rounded lugs, a¹, and each link being composed of a plurality of plates held together transversely by rivets, g, engaging apertures, f, formed in the plates, a, just behind the lugs, a¹. The clearance apertures, a², besides affording space for the interlocking lugs, a¹, provide room for the rivets, g, as is clear in Fig. 2. Thus, as one link of the chain changes its angular relation to the next link by the rocking of its bearing lugs, a¹, upon the bearing lugs, a¹, of the other link, the connecting rivet, g, in one link traverses a curved path in the clearance apertures, a², of the plates of the other link. And the same may be said of the rivet, a³, of said other link with respect to the clearance aperture, g, of the first link.

By properly forming the clearance aper-

tures, a^2 , they may perform the additional function of guards to prevent the bearing lugs, a^1 , from slipping upon each other. The edges of the apertures, a^2 , are shaped to conform to the paths of the terminal edges, a^4 , of the lugs, a^1 , as said lugs rock upon each other and move within the apertures, a^2 , so that in any correct position of a lug, a^1 , its ends, a^4 , are in contact with the edges of the clearance aperture, a^2 , in the link plate into which the lug, a^1 , extends.

Figs. 5 to 10, inclusive, illustrate a modified form of drive chain which is made up of two forms of link plates instead of having all the plates exactly alike, as in the form shown in Fig. 1. In Fig. 5 the resulting types of links are indicated at B and C, respectively, while the detail construction of the plates is shown in Figs. 7 and 8, and in modified arrangement in Figs. 9 and 10.

The links, B, are each formed of a plurality of plates, b , each having a semi-circular aperture, b^1 , at each end and a bearing lug, b^2 , folded out from said aperture to extend laterally from the plate at one side and formed with a straight bearing face, b^3 , diametrically positioned with respect to the aperture, b^1 . The other type of link plate, C, is formed with segmental apertures, c^1 , and bearing lugs, c^2 , folded out therefrom to project from one surface of the plate, and said lugs, c^2 , are obtusely angular or V-shaped so as to provide substantially a line bearing at c^2 , for co-operation with the flat bearing surfaces, b^3 , of the link plate, B, such apex or bearing line, c^3 , being disposed at the center or axis of the aperture, c^1 . Thus it will be evident that if the plate, B, be lapped at one end upon the plate, C, with its aperture, b^1 , concentric with the aperture, c^1 , the apex, c^3 , of the bearing lug, c^2 , will be in contact with the flat bearing lug, b^2 , substantially along the common axis of the apertures, b^1 and c^1 , and if the plate, C, is swung about such common axis, the ends, c^4 , of its lug, c^2 , will traverse the arc of the aperture, b^1 , while the ends of the bearing lug, b^2 , will do likewise upon the arc of the opening, c^1 , said apertures, b^1 and c^1 , remaining concentric throughout the movement.

As indicated in Figs. 9 and 10, it is not essential that both bearing lugs of one plate be of the flat faced form, but the link plates 55 may be made like the types, D and E, respectively, each of which has a flat faced bearing lug at one end and an angular lug at the other end. The lugs, d^x and d^y , of the plate, D, extend from the opposite side of said plate as compared with the lugs, e^x and e^y , of the plate, E, so that when such plates, D and E, are lapped upon each other, the bearing lug of each plate shall enter the clearance aperture of the other plate providing a bearing between the two plates

along a line equal in length to the combined thickness of the two plates, and located in the common axis of the clearance apertures.

In all styles of link plates shown, small apertures, f , are formed in the flat walls of the plates just back of each bearing lug,—that is, at the side of said lug opposite its bearing surface, and each complete link of the chain is made up by assembling side by side a number of similar links and securing them together by rivets, g extending through the registered apertures, f . It will be understood that by temporarily inserting a thin piece of material between any two adjacent plates while riveting the plates together, the rivets, g , may be prevented from unduly binding the plates laterally in a manner to cause excessive friction between them at the joints, so that except for the unavoidable friction between the surfaces of adjacent plates, the folding motion at each joint is a mere rocking movement of the simplest form,—the rocking of a "knife edge" upon a flat bearing surface.

It is evident that the forms of the link plates herein shown may be very economically produced as stampings, being treated by any suitable hardening process subsequent to their formation, so that by virtue of their bearing lugs thus formed integrally with the plates themselves, they provide their own pintles and no further elements are required to complete the chain except the very cheap and simple rivets, g .

While the use of the angular or V-shaped bearing lugs somewhat simplifies the problem of designing the link plates, since the rocking motion resulting is just the same as though the plates were connected with simple pivots, the curved lugs shown in Figs. 1 to 4 are preferred because in their rocking motion their line of contact is constantly changing with a resulting distribution of wear on the bearing surfaces which is not obtainable with the angular lugs. And further, with the curved lugs there will be a minute flattening of the curves under heavy loads with a corresponding increase of actual bearing surface which if it occurred in the angular lug would tend to disturb the correctness of its rocking motion, perhaps causing binding between the terminal edges of the lug and the circularly curved clearance aperture in which it swings.

I claim:—

1. A chain composed of link plates, each having a bearing lug extending laterally from the surface of the plate with a convexly curved bearing surface adapted to rock upon the similar surface of a bearing lug of the next link, each plate having a clearance aperture of general triangular shape bounded on one side by said curved bearing surface of the lug and on the other

two sides by curves conformed to the paths of the edges of the coöperating lug in its said rocking movement, to accommodate said coöperating lug of the connected link.

5. 2. A chain composed of link plates, each having a bearing lug extending laterally from the surface of the plate with a convexly curved bearing surface adapted to rock upon the similar surface of a bearing lug of the next link, each plate having a clearance aperture of general triangular shape bounded on one side by said curved bearing surface of the lug and extending therefrom to accommodate the coöperating 10 lug of the connected link, the remaining outline of such clearance aperture being curved to conform to the paths of the edges of said coöperating lug in its said rocking movement for contact with the said coöperating 15 lug throughout said movement.

20. 3. A rocker joint chain composed of mul-

tiplate links, each plate of one link having an integrally formed bearing lug extending laterally from the face of the plate, laterally adjacent plates of the next link having integral bearing lugs extending respectively for contact with the lugs of the first link to form a rocking joint therewith, the plates of each link having clearance apertures partially bounded by the bearing faces of the lugs 25 and positioned to accommodate the lugs of the other link, and transversely disposed rivets for laterally joining the plates of each link, said rivets being positioned back of the bearing faces of the lugs within the 30 clearance apertures of the next adjacent links.

In testimony whereof I have hereunto set my hand at New York, N. Y. county, this 10th day of October, 1916.

JULIA B. STEWART,
Executrix of John K. Stewart, deceased.
